UNITED STATES PATENT OFFICE

GUSTAV J. SENGBUSCH, OF MILWAUKEE, WISCONSIN

INKSTAND

Application filed June 25, 1930. Serial No. 463,770.

This invention relates to an ink stand construction and more particularly to an ink stand particularly designed for facilitating the filling of fountain pens.

5 The main object of my invention is to provide a device of the character referred to which will facilitate the filling of a fountain pen while being effective to prevent immersion of a portion of the pen holder or fountain pen barrel into the ink or other writing fluid, thereby maintaining the pen barrel clean and ready for instant use upon filling.

10 Other objects of my invention are to provide a device of the class described of simple construction which is easy to make, effective and not apt to get out of working order; to provide an arrangement which will normally afford a full supply of ink for filling the pen; to provide an arrangement wherein the opening to the ink supply is normally kept closed so as to prevent evaporation of the ink; to provide an arrangement wherein the pen being filled is effective to maintain the closure for the filling opening in open position while 15 the pen is being filled, and wherein the closure automatically adjusts itself to closed position upon removal of the pen.

20 Other objects and advantages of my invention will be understood by reference to the following specification and accompanying drawings, in which I have illustrated a selected embodiment of my invention.

25 In the drawings:

Fig. 1 is a plan view of my improved ink stand, and

30 Figs. 2 and 3 are sections on the line 2—2 of Fig. 1, Fig. 2 showing the parts in open position, while Fig. 3 illustrates the parts in closed position.

35 Referring now to the drawings, my improved ink stand includes a main reservoir 5 made of any suitable material, for instance glass. The main reservoir 5 embodies a chamber 6 having a pit 7 in its bottom. A cover 8 of suitable material, for instance hard rubber, is mounted on the reservoir 5, preferably by means of screw threading as indicated at 9, or by other means so as to be removable.

40 An auxiliary reservoir 10 is disposed with-

55 in the main reservoir and is adjustable vertically from lower or depressed position as illustrated in Fig. 3 to up or raised position as illustrated in Fig. 2. The auxiliary reservoir 10 is preferably of such size and shape that it fits in the pit 7 and is accordingly capable of displacing substantially all of the writing fluid in the pit. The side wall of the auxiliary reservoir 10 is preferably slightly higher than the depth of the pit, whereby the 60 fluid displaced from the pit will overflow the side wall of the auxiliary reservoir and fill the same. By the slightly greater height of the side wall of the auxiliary reservoir as best shown in Fig. 3, the tendency for sediment to flow into the auxiliary reservoir is 65 more or less overcome.

70 The auxiliary reservoir 10 is mounted for vertical adjustment by means of a stem 11 which is secured at its lower end to the auxiliary reservoir by means of a screw threaded shank 12 which engages a tapped opening 13 formed in a boss 14 which projects upwardly from the bottom of the auxiliary reservoir. The stem 11 is slidably mounted in a suitably 75 apertured boss 15 which depends from the cover 8. As best shown in Fig. 2, the boss 14 of the auxiliary reservoir, is preferably of greater diameter than the stem 11 so that the boss 14 will engage the boss 15 of the 80 cover to limit upward adjustment of the auxiliary reservoir.

85 The cover 8 is provided with a plurality, three in this instance, of openings 16, 17 and 18, which permit the pen point portion of a fountain pen or other pen to be inserted into the auxiliary reservoir when the latter is in up position as illustrated in Fig. 2. The openings 16, 17 and 18 are preferably of various sizes so as to be effective to limit the 90 extent of immersion of the pen point and to prevent the lower end of the fountain pen barrel or pen holder from being immersed in the writing fluid in the auxiliary reservoir. By this means, it is obvious that a fountain pen may readily be filled without danger and without the possibility of dipping the pen holder or barrel in the ink with consequent inconveniences. Of course, it will be 95 understood that fountain pens are now to 100

be had in a wide range of sizes and that certain large sizes of pens that would fit in the opening 18 would not fit in the opening 16, and also that some of the smaller sizes of 5 pens which would be limited in immersion by the opening 16, would not be so limited by the opening 17 or 18; hence, the desirability of the various sized openings.

For closing the openings 16, 17 and 18, I 10 provide a unitary closure member 19 which is mounted on the stem 11 so as to be adjustable therewith. The closure 19 is mounted on the stem by means of a threaded shank 20 formed integral with the stem and a handle 15 or top element 21. The stem 20 passes through an opening 22 provided in the closure member 19, and the handle or top 21 is tapped to fit the threaded shank 20 as clearly shown in Fig. 3. It will be seen that the 20 knob 21 serves to clamp the closure member 19 against the end of the stem 23.

The closure member may be generally described as being shaped like a three-leaf clover. By inspection of Fig. 1, it will be 25 seen that the closure embodies three main portions 24, 25 and 26 which are respectively adapted to close the openings 16, 17 and 18. The recesses between the respective closure parts 24, 25 and 26 constitute seats 27, 28 30 and 29 which are designed to position the pen substantially vertically coaxial with the respective openings 16, 17 and 18 in the cover. For causing the closure member to rotate from its closed position as indicated 35 in broken lines in Fig. 1 to its open position as illustrated in full lines in Fig. 1, I provide the stem or post 11 with a spiral groove 30 into which a pin or stud 31 projects from the depending boss 15 of the cover. It will 40 be seen that when the auxiliary reservoir 10 is manually adjusted upwardly from the pit position shown in Fig. 3 to the pen filling position shown in Fig. 2, it will be necessarily rotated in accordance with the pitch 45 of the spiral groove 30. By this means, the clover-shaped closure member is more or less automatically caused to assume its open position as an incident to raising of the auxiliary reservoir.

50 In the present instance, I have shown the spiral groove 30 as having such a pitch that the auxiliary receptacle stem and other parts connected to the stem 11 are rotated only approximately $\frac{1}{6}$ of a complete revolution. 55 This is sufficient to permit the insertion of a pen as shown in Fig. 2. It will be understood that when the pen is in filling position as shown in Fig. 2, the pen acts as a lock to prevent downward movement of the closure 60 inasmuch as the closure can not then rotate as required. If desired, the pitch of the spiral groove 30 may be increased so that the closure member is caused to rotate a half revolution or more to open position so that 65 the locking effect of the pen when in filling

position will be more pronounced than with the arrangement illustrated. However, for present purposes, I prefer the arrangement shown.

A washer 32 may be interposed between the 70 cover and upper edge of the main reservoir to provide a tight joint therebetween, and the said washer may conveniently be anchored to the cover by being seated in an undercut seat 33 as shown. By this means, loss of 75 the washer 32 when the cover is removed from the reservoir, is avoided.

The cover 8 is preferably provided with a recessed portion 34 shaped to receive the 80 clover shaped closure 19 and each opening 85 16, 17 and 18 is located in one of the leaf portions of the said recess 34. This recessed arrangement prevents ink, which might accidentally be drawn up to the edges of the openings, from spreading over a normally 85 exposed area on the cover.

I am aware that changes may be made in the above described structure without departing from the spirit of my invention, the scope of which should be determined by 90 reference to the following claims, the same being construed as broadly as possible consistent with the state of the art.

I claim as my invention:

1. In a device of the class described, the 95 combination of a reservoir for writing fluid, a cover over said reservoir having an opening therein of such size as to permit only a predetermined end portion of a writing instrument to be passed therethrough for immersion in fluid in said reservoir, and a closure for said opening, adapted when in open position, to position the writing instrument in predetermined relation to said opening.

2. In a device of the class described, the 100 combination of a reservoir for writing fluid, a cover over said reservoir having an opening therein of such size as to permit only a predetermined end portion of a writing instrument to be passed therethrough for immersion in fluid in said reservoir, and a closure for said opening arranged to be held in open position by the holder of the pen being immersed and to automatically move to 105 closed position upon withdrawal of the pen and pen holder.

3. In a device of the class described, the 110 combination of a main reservoir for writing fluid, an auxiliary reservoir within said main reservoir adapted to be filled with fluid therefrom by submersion therein, a cover over said main reservoir having an opening therein of such size as to permit only a predetermined end portion of a writing instrument to be 115 passed therethrough for immersion in the fluid in said auxiliary reservoir, and a closure for said opening arranged to be automatically held in open position by a part of the pen being immersed and to automatically 120

125 130

ly move to closed position upon withdrawal of the pen.

4. In a device of the class described, the combination of a main reservoir for writing fluid, a cover for said main reservoir, an auxiliary reservoir vertically adjustably mounted in said main reservoir, means outside of said main reservoir, for facilitating manual adjustment of said auxiliary reservoir, said cover having a restricted opening for permitting the pen point portion of a fountain pen to be passed through the cover and immersed in fluid in said auxiliary reservoir when the latter is in up-position.

15 5. In a device of the class described, the combination of a main reservoir for writing fluid, a cover for said main reservoir, an auxiliary reservoir vertically adjustably mounted in said main reservoir, means outside of said main reservoir for facilitating manual adjustment of said auxiliary reservoir, said cover having a restricted opening for permitting the pen point portion of a fountain pen to be passed through the cover and immersed in fluid in said auxiliary reservoir when the latter is in up-position, and a closure for said opening, mounted so as to be opened as an incident to adjustment of said auxiliary reservoir to up-position.

30 6. In a device of the class described, the combination of a reservoir for writing fluid, a cover for said main reservoir having a plurality of respectively different sized openings for permitting different sized pen points to be passed through the cover and into the fluid in said reservoir, said openings being of such size as to limit the extent of immersion of the pen point by engagement with a portion of the pen holder, and a unitary closure for said openings adjustable as a unit to open and closed positions.

45 7. In a device of the class described, the combination of a main reservoir for writing fluid, an auxiliary reservoir within said main reservoir and mounted so as to be submersible in the fluid in said main reservoir to fill said auxiliary reservoir, a cover for said main reservoir having a plurality of respectively different sized openings for permitting different sized pen points to be passed through the cover into the fluid in said auxiliary reservoir, said openings being of such size as to limit the extent of immersion of the pen point by engagement with a portion of the pen holder, and a unitary closure for said openings adjustable as a unit to open and closed positions.

55 8. In a device of the class described, the combination of a reservoir for writing fluid, a cover for said main reservoir having a plurality of respectively different sized openings for permitting different sized pen points to be passed through the cover and into the fluid in said reservoir, said openings being of such size as to limit the extent of immersion of

the pen point by engagement with a portion of the pen holder, and a closure for said openings, horizontally rotatable and vertically adjustable from closed to open position, said closure being provided with means for positioning a pen with respect to the respective openings when said closure is in open position.

9. In a device of the class described, the combination of a main reservoir having a pit in its bottom, a cover for said main reservoir, an auxiliary reservoir fitting in said pit so as to be capable of displacing substantially all of the fluid therefrom, means for vertically adjustably mounting said auxiliary reservoir in said cover for movement into and out of said pit, means for facilitating manual adjustment of said auxiliary reservoir, an opening in said cover for permitting a pen point to be passed therethrough and into said auxiliary reservoir, and a closure mounted for adjustment in its own plane to open and closed position as an incident to vertical adjustment of said auxiliary reservoir.

10. In a device of the class described, the combination of a main reservoir for writing fluid, said reservoir having a pit in its bottom, a cover for said main reservoir, an auxiliary reservoir fitting in said pit so as to be capable of displacing substantially all of the fluid therefrom, means for vertically and rotatably adjustably mounting said reservoir in said cover, means for facilitating such adjustment of said auxiliary reservoir manually, said cover having an opening therein for permitting the pen point portion of a fountain pen to be inserted through said cover into said auxiliary reservoir when the latter is in up-position, and a closure mounted for vertical and rotary adjustment in its own plane to open position as an incident to upward adjustment of said auxiliary reservoir.

11. In a device of the class described, the combination of a main reservoir for writing fluid, said reservoir having a pit in its bottom, a cover for said main reservoir, an auxiliary reservoir fitting in said pit so as to be capable of displacing substantially all of the fluid therefrom, means for vertically and rotatably adjustably mounting said reservoir in said cover, means for facilitating such adjustment of said auxiliary reservoir manually, said cover having a plurality of different sized openings for permitting predetermined sizes of pen points to be inserted through said cover into said auxiliary reservoir when the latter is in up-position, while also preventing passage of the adjacent portion of the pen holder through said cover, and a closure for said openings mounted for adjustment to open position as an incident to vertical and rotary adjustment of said auxiliary reservoir.

12. In a device of the class described, the combination of a main reservoir for writing

fluid, said reservoir having a pit in its bottom, a cover for said main reservoir, an auxiliary reservoir fitting in said pit so as to be capable of displacing substantially all of the fluid therefrom, means for vertically and rotatably adjustably mounting said reservoir in said cover, means for facilitating manual vertical and rotary adjustment of said auxiliary reservoir, said cover having a plurality of different sized openings for permitting predetermined sizes of pen points to be inserted through said cover into said auxiliary reservoir when the latter is in up-position while also preventing passage of the adjacent portion of the pen holder through said cover, and a closure for said openings mounted for adjustment to open and closed positions as an incident to vertical rotary adjustment of said auxiliary reservoir, said closure having seats adapted to receive and position the pen holder in predetermined relation to said openings.

13. A device as defined in claim 9, wherein said opening is restricted to permit limited immersion of a pen, and said closure functions when in open position to retain said pen in said opening.

14. A device as defined in claim 10, wherein said opening is restricted to permit limited immersion of a pen, and said closure functions when in open position to retain said pen in said opening.
